UNITED STATES PATENT OFFICE.

GEORGE A. DESENFANT, OF SAN FRANCISCO, CALIFORNIA.

SCARF-CLASP.

1,202,680.

Specification of Letters Patent.

Patented Oct. 24, 1916.

Application filed November 23, 1914. Serial No. 873,654.

To all whom it may concern:

Be it known that I, GEORGE A. DESENFANT, a citizen of the United States, residing in the city and county of San Francisco, State of California, (whose post-office address is 165 Post street,) have invented new and useful Improvements in Scarf-Clasps, of which the following is a specification.

This invention relates to ornamental utility ties; more particularly to loops or c' for securing scarfs or kerchiefs about the neck of the wearer, which is one of the objects of this invention.

Another object is to provide an ornamental means for securing the ends of the scarf without knotting the same.

A further object is to provide a clasp that will stay where placed on the scarf, and perform its function without injuring the texture of the scarf.

Other objects and advantages will appear as the description progresses.

In the drawing accompanying and forming part of the present specification, to which like reference characters have been applied, a simple form of putting this invention into practice is shown. I do not wish to be understood as confining this invention to the disclosures made in said drawing and description, as many variations may be introduced, within the spirit of this invention, as defined in the claims succeeding the said description.

The handkerchief as an article of neck-wear has an established place in the dress of those living an outdoor life, particularly on cattle ranges and on horse-back. It is desirable to provide some means for quickly and easily adjusting the kerchief by some device, that will maintain its position without injury to the scarf, and it is also desirable that the device be of an ornamental nature. Knotting a kerchief about the neck is unsatisfactory for several reasons. The knot is liable to be drawn too tight, rendering its untying laborious, and it is hard to place a knot in just the right place for comfort, and to present the proper appearance. This device fulfills all the requirements of its objects, lies flat, and adds weight to the scarf, tending to maintain it in the proper position about the neck of the wearer.

In the drawings: Figure 1, is a front elevation of a scarf clasp constructed in ac-

cordance with this invention, and applied to the opposite ends of a square kerchief folded obliquely. Fig. 2, is an enlarged detail in front elevation of the clasp. Fig. 3, is an end elevation of the same. Fig. 4, is a rear elevation of the same. Fig. 5, is a plan or edge view of the same.

In detail the construction illustrated the drawings includes, preferably a single strip of metal 1 bent backward upon itself at 2 and 3 forming the two spring extensions 4 and 5, lying behind the front portion 1. The ends of these extensions are preferably slightly separated, to permit the passage of the scarf between, to enter the opening 6; but the ends may be permanently joined, to form an endless loop if desired. The longitudinal edges 7 and 8 are preferably curled inward, so that the opening 6 is narrower than the distance between the plane of the body 1 and the extensions 4 and 5. This contraction of the opening permits the scarf to expand within, above and below the clasp; the spring tension of the extensions 4 and 5, tending to clamp the edges 7 and 8 against the scarf, to maintain it in any position to which it may be adjusted, by holding the ends of the scarf and sliding the clasp thereon. The edges 7 and 8 are preferably smooth, so as not to injure the scarf in the adjusting operation. The permanent adjustment of the clasp is insured by the addition of the relatively blunt points 9, 10, and 11 directed inward toward the scarf; the point 9 being formed preferably in the center of the clasp and the points 10 and 11 on the extensions 4 and 5 respectively, and spaced on opposite sides from the central point 9.

The clasp is conveniently applied in the following manner: The kerchief properly folded is placed about the neck of the wearer, and the opposite ends 12 and 13 grasped between the fingers of the left hand; the clasp is then taken in the right hand and the ends 12 and 13 forced into the opening 15, between the ends of the extensions 4 and 5, until the ends of the kerchief enter the opening 6. The attenuated ends of the kerchief presenting a relatively small bulk the clasp is easily placed thereon. With the clasp inserted on the ends of the kerchief, it is slid upward to the desired position, where its spring tension will clasp it securely, to hold the ends of the kerchief as

desired. The clasp is readily removed by inserting the finger nail under the point 9, and withdrawing the end 12 of the kerchief from the clasp; this reduces the bulk 5 of the material within the clasp, facilitating the removal of the other end 13 of the kerchief therefrom, without danger of the points 10 and 11 destructively engaging it.

The peculiar contour given to the clasp 10 as illustrated in the drawing, adds materially to its clinging qualities in its engagement with the kerchief, as well as adding to its ornamental value. This contour may be varied to suit the taste of the designer or 15 to add to the utility of the clasp. The width 2 of the strip 1 being reduced at the bends 3, makes it readily possible to bend the extensions 4 and 5 inwardly, by compression between the fingers to vary the width of 20 the opening 6, to accommodate the clasp to the bulk of the material clamped between.

Other uses for this device as illustrated will suggest themselves to users.

The clasp may be embellished by superficial ornamentation, and the addition of 25 such medallion effects as those illustrated

in the drawing, consisting of a "bucking bronco" soldered to the face of the clasp.

Having thus described this invention what I claim and desire to secure by Letters Patent is:

1. A clasp including a strip of material bent back upon itself in opposite directions, and having inturned edges; inturned points on said backward extensions; and an in-turned point on the body portion between 35 said first mentioned points.

2. A clasp formed from a single strip of material, bent back upon itself in opposite directions, the backward extensions having 40 their terminals in a plane parallel to the plane portion of the body-portion in close proximity to each other, said extensions having inturned lateral edges, and an in-turned point on the body portion between 45 the said terminals.

In testimony whereof, I have hereunto set my hand this 14th day of November 1914.

GEORGE A. DESENFANT.
